APPARATUS FOR MANUFACTURING BRICKS

Neal W. Helm, Caruthersville, Mo.

Application March 11, 1940, Serial No. 323,413

5 Claims. (Cl. 25—48)

This invention relates to new and useful improvements in apparatus for manufacturing bricks.

One object of the invention is to provide an improved brick-making apparatus which is simple in construction and which is readily portable, whereby the bricks may be manufactured at the place of use which obviates the necessity of hauling or transporting said bricks from a manufacturing plant to the various places where said bricks are used in construction work.

An important object of the invention is to provide an improved brick-making apparatus which is automatic in its operation and which has a capacity sufficient to furnish enough bricks for the ordinary or usual construction job on which it is employed.

Another object of the invention is to provide an improved apparatus, of the character described, having a shuttle means for moving a plurality of pallets or forms successively beneath a feed hopper and then beneath a press, the latter serving to apply pressure to the material in the forms to shape the brick; the press and shuttle means being synchronized in their actuation, whereby an automatic and continuous operation is had.

Still another object of the invention is to provide a brick-forming apparatus wherein a plurality of angular forms or pallets are movable between confining members and into position beneath a press, the forms being disposed in a single line with adjacent forms in engagement, whereby the angular forms coact with each other and with the confining members to form molds into which the brick material is introduced; the arrangement of the angular forms making it possible to employ a single actuator for imparting movement to all of said forms.

A further object of the invention is to provide an improved apparatus, of the character described, wherein the angular forms are unconnected from each other, being merely in contact with each other, said forms being movable, successively, beneath the press which enters the form to press the material therein; the apparatus including means for locking the unconnected forms against movement during the pressing operation, whereby proper forming of each brick is assured.

A particular object of the invention is to provide an apparatus of the character described, wherein each form, as well as the press ram, are so constructed that the finished brick formed by these parts has the longitudinal edges of its outer end rounded or chamfered, whereby when employed in building construction, sharp edges are eliminated and danger of breaking or cracking such edges is obviated.

A construction designed to carry out the inven-

tion will be hereinafter described, together with other features of the invention.

The invention will be more readily understood from a reading of the following specification and by reference to the accompanying drawings, in which an example of the invention is shown, and wherein:

Figure 1 is a side elevation of an apparatus constructed in accordance with the invention,

Figure 2 is a plan view thereof,

Figure 3 is an enlarged, transverse, vertical, sectional view, taken on the line 3—3 of Figure 2,

Figure 4 is an enlarged, horizontal cross-sectional view, taken on the line 4—4 of Figure 1,

Figures 5 to 7 are enlarged, vertical sectional views, illustrating the various operating positions of the shuttle means.

Figure 8 is an isometric view of the end of the shuttle means,

Figure 9 is an isometric view of the press ram or block, and

Figure 10 is a partial view of a wall constructed of the bricks formed by the apparatus.

In the drawings, the numeral 10 designates a frame or support which is formed of a pair of longitudinal angle bars 11 which extend parallel to each other. Inclined legs 12 have their upper ends secured to the ends of the bars 11 and support the frame at the desired height. The lower ends of each pair of legs may be connected by braces 13 which reinforce and strengthen the same. An elongate plate 14 is supported on the angle bars 11, being suitably secured thereto as by welding, and the ends of the plate extend beyond the extremities of the frame, as is clearly shown in Figures 1 and 2. This plate is relatively narrow in width and forms a working table or platform.

A pair of channel bars 15 are secured to the longitudinal edge portions of the platform and the channels extend parallel to each other. One end of each channel is located above the end of the angle bar 11 of the frame, while the other end thereof terminates short of the opposite end of said frame (Fig. 1). The channel bars 15, together with the plate 14, form an elongate trough or guideway 16.

A supporting structure or framework is mounted above one end of the plate or table 14 and includes horizontally extending angle members 17 which are secured to the upper ends of vertical standards 18. In addition to the standards, four angle bars 19 (Fig. 2) connect the channels to the members 17. Each pair of angle bars 19 have a flat plate 20 welded, or otherwise secured thereto, and the space between the plates provides a vertical guide for a press ram or block 21. The ram is movable vertically between the guide so formed, and is arranged to move downwardly be-

tween the channels 15 which form the trough 16. The ram or block has a flat bottom and one transverse edge of said bottom is provided with an elongate lip or flange 22 which depends in a plane therebelow (Fig. 9). The upper end of the ram or block has an upstanding ear 23, and the lower end of a vertically reciprocable, rod 24 is pivotally connected to said ear.

The upper end of the rod extends upwardly between the angle members 17 (Figure 3) and is pivoted to one end of an operating lever 25. The lever is mounted on a transverse shaft 26 which spans the space between the members 17 and has its ends journaled in bearings 27, which bearings are supported on, and secured to, short channel elements 28. These channel elements rest upon and are preferably welded to the top of the angle members 17.

The lever 25 overlies the space between the angle bars 17 and has a weight 25a secured to its other end. The weight urges the lever downwardly into engagement with the periphery of a cam 29 which is mounted on a rotatable shaft 30 and which is located beyond the pivot shaft 26 of the lever. The shaft extends transversely between the angle members 17 and has its ends journaled in bearing collars 31 which are bolted to the top of said members (Fig. 3). One end of the shaft projects through its bearing collar and has a gear 32 keyed, or otherwise secured thereon. The gear is in constant mesh with a drive pinion 33 which is secured on a rotatable shaft 34. The shaft is mounted in bearing collars 35 which rest upon the angle members 17 and one end of said shaft has a drive pulley or wheel 36, over which an endless drive belt 37 extends. The belt is driven from any suitable source (not shown) and serves to rotate the drive pulley to rotate the pinion 33.

Rotation of the pinion 33 imparts a rotation to the gear 32, whereby the cam shaft 30, and cam 29 mounted thereon, are rotated. Since the outer end of the lever 25 is in constant engagement with the periphery of the cam, being held so by the weight 25a, a rotation of said cam swings said lever, whereby the rod 24 secured to the lever is reciprocated vertically. The lower end of the rod is fastened to the press ram or block 21 and reciprocation of said rod results in a reciprocation of the ram within its guide formed by the plates 20. The length and mounting of the lever, as well as the size of the cam 29, are such that the press ram or block moves from the position shown in dotted lines to the position shown in full lines in Figure 3, and back again to the dotted line position, during one complete revolution of said cam. The formation of the cam is such that the press ram is in its lowermost position between the channels 15 during a minor portion of the cam rotation.

A plurality of forms or pallets 38 are movable along the plate or table 14 and beneath the press ram or block 21, as will be explained. Each form comprises an angle member having a horizontal flange 39 and a vertical flange 40 (Fig. 8). The flanges are integral at the intersection of such flanges a fillet 38a is provided whereby a sharp corner at such intersection is eliminated. The width of each member 38 is substantially equal to the transverse width of the trough or guideway 16 formed by the channels 15, whereby said member has its ends slidably engaging said channels. The height of the vertical flange 40 of each angle 38 is substantially equal to the height of the channel bars 15 and manifestly,

when a plurality of the angular forms are placed within the trough or guideway, they co-act with each other and with the channels to provide a plurality of rectangular shaped open-top molds, which are adapted to receive the material of which the bricks are to be formed.

For introducing the material into the molds, a hopper 41 is mounted on the channels 15 and spans said channels, said hopper having a discharge opening 42 in its bottom. The hopper may be supplied with material from a chute 43 which extends from a suitable source of supply. The forms 38 are movable along the table or plate 14 in a direction to the left in Figure 3, and obviously, said forms first pass beneath discharge opening of the hopper to receive the material therefrom and then move beneath the press ram or block 21, which applies pressure to said material to shape the same into a brick. It is noted that any suitable material, such as cement, concrete or the like may be employed and it is preferable to use a relatively "dry mix" so that the material introduced into the forms is not too liquid and will not flow freely of its own accord.

For successively moving each form 38 beneath the press ram 21, a shuttle plate 44 (Fig. 5 to 8) is mounted on one end of the table 14 and is capable of a limited sliding or reciprocating movement longitudinally thereof. The shuttle plate is secured to a transverse bar 45 by means of vertical pins 46, which pins extend through longitudinal slots 47 provided in the table. The bar is disposed below the table 14 and has its ends projecting through slots or openings 48 in the angle bars 11 of the support 10. The bar 45 may move or reciprocate within the slots 48 and when so moved, imparts a reciprocation to the shuttle plate 44, said plate being guided by the pins 46 moving through the slots 47.

Each projecting end of the bar 45 has one end of an elongate connecting rod 49 pivoted thereto and the other end of each rod is pivotally secured to a crank arm 50 (Figs. 1 and 2). The crank arms 50 are keyed, or otherwise fastened on the ends of the cam shaft 30 and manifestly, when the cam shaft is rotated to actuate the press ram, as has been explained, the shuttle plate 44 is reciprocated through the medium of the crank arms 50, connecting rods 49 and reciprocating bar 45. The construction of the cam and the arrangement of the crank arms, and their associate parts, are such as to synchronize the operation of the press ram with the reciprocation of the shuttle means.

The outer end of the shuttle plate 44 is movable through clips or stop lugs 51 (Fig. 8) which overhang the marginal portions of the plate and which are rigidly fastened to the table 14. When the forms 38 are placed on the table, as shown in Figures 3 and 5, the edge of one of said forms, indicated at A in Figure 5, is adjacent the inner edge of the shuttle plate 44. Additional forms are placed on the plate 44 and the form at the outer end of the plate, indicated by B, abuts the fixed clips or lugs 51. In the position shown in Figure 5, the shuttle plate is at its innermost position having just moved the forms on the table 14 in a direction to the left in Figures 1, 3 and 5 to 7.

In the operation of the apparatus, assuming the shuttle plate 44 to be in the position shown in Figure 5, the press ram or block 21 is in the position shown in dotted lines in Figure 3. As the cam 29 rotates in a counter-clockwise direction,

the operating lever 25 is swung on its pivot 26, whereby the press block 21 is moved downwardly into the mold which is provided by the forms 38 located below the block. As the press block moves downwardly into this mold, said block applies a pressure to the material which is disposed within said mold and presses said material into the proper shape. By observing Figure 3, it will be seen that when the block has moved to its lowermost position, the material has been pressed into the shape of a brick and due to the curved lip 22 at one longitudinal edge of the block, the upper longitudinal edge of the brick is rounded, rather than angular. One of the lower longitudinal edges of the brick is also rounded in a similar manner due to the fillet 38a which is formed on each angle form 38. Thus, two corners of the brick, are rounded and these corners are on the outer face of the wall, when the bricks are assembled to form such wall as is clearly shown in Figure 10. The two rounded corners or edges on each brick not only give the finished wall a better appearance, but also prevent chipping or breaking off of these corners after the wall is complete.

During the time that the press ram or block 21 is moving downwardly within the mold to press the material therein into a proper shape, the crank arms 50 and connecting rods 49 are moving the operating bar 45 laterally through its slot 48 whereby a movement is imparted to the shuttle plate 44. The direction of movement of the shuttle plate is to the right in Figures 5 to 7, whereby said plate moves outwardly with relation to the table 14. As has been explained, when the plate is in the position shown in Figure 5, one of the angle forms A is abutting the inner edge of said plate and upon movement of the plate, this edge moves away from such angle A. To prevent this angle from following the plate 44 as the same moves outwardly on the table, a pair of spring-pressed latches or dogs 52 are provided. These dogs are mounted on ears 53 which extend outwardly from the channel members 15, as is fully shown in Figures 2 and 4. One end of each dog or latch extends inwardly through an opening 54 provided in the channel 15 and this end is formed with a keeper 55. The opposite end of the latch is urged outwardly away from the channel 15 by means of a coiled spring 56, whereby the keeper 55 is urged into the path of the angular forms 38.

As each angle 38 moves past the keepers 55 of the latches 52, said latches are depressed so as to permit the angle to pass thereby. Obviously, after the vertical flange 40 of the angle moves past the keeper, the spring 56 automatically moves the keeper in behind said flange and prevents the flange from moving in a direction to the right in the Figures 5 to 7.

As the shuttle plate 44 moves away from the angle A, as shown in Figure 6, its inner end is slid from beneath the next angle indicated at A', whereby said angle may fall downwardly onto the table 14. By the time the press block 21 has shaped the material within the mold therebelow and has returned upwardly to the position shown in dotted lines in Figure 3, the shuttle plate 44 has completed its outward movement, as shown in Figure 7. At this time, the angle A' has moved downwardly onto the table, whereby the edge of its horizontal flange 39 is adjacent the edge of the shuttle plate 44. Due to the control of the shuttle plate 44 by the crank arm 50, said plate then moves inwardly on the table and back

to the position shown in Figure 5. As it moves to such position, its inner end engages the angle A' and pushes the same to the left on the table 14. The movement imparted to this end angle A' is transmitted through the other angles, whereby all of said angles are moved on the table. Movement of the shuttle plate continues until the angle A' has moved to the position past the latches 52, whereby the angle A' then assumes the position which the angle A has in Figure 5. Of course, when the shuttle plate has moved inwardly its entire distance, there is a space between the end angle B and the fixed clips 51 and into this space another angle is introduced, as indicated by dotted lines in Figure 5.

The movement of the shuttle plate 44 is such that the next mold is moved beneath the press ram or block 21 and after the plate has completed its movement, the cam 29 has again moved to a position ready to lower the press block into the next succeeding mold. In this manner, the press block is synchronized in its operation with the reciprocation of the shuttle plate and the operation is entirely automatic. Since the feed hopper 41 is disposed in advance of the press block 21, it will be obvious that each mold is filled with the material as it passes beneath said hopper and prior to its movement beneath the press block. The end of the table 14, which may be termed the discharge end, is disposed in horizontal alignment with a conveyor belt 57, which belt may be mounted on pulley 58 and may be driven by any suitable means. As the bricks which have been formed, together with the angle forms 38, move off of the table 14, they move onto the conveyor belt 57 which may take said bricks and angles to any suitable point.

From the above, it will be seen that a simple and efficient brick manufacturing apparatus is provided. The device is readily portable, whereby it may be moved onto the job where the bricks are to be used. The use of the machine obviates the necessity of hauling or transporting brick necessary for the particular work. All of the operating parts of the mechanism are driven from a single drive or source of power which may be an engine, motor or other prime mover. Obviously, the forms or angles 38, as well as the transverse width of the trough 16 may be varied to vary the size of the mold, as desired.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A brick manufacturing apparatus including, a stationary support, upstanding sides on said support forming a trough, a plurality of angular unconnected elements movable through the trough and arranged in abutting relation with each other, said elements co-acting with each other and with the sides to provide substantially rectangular molds, means for introducing a cementitious material into the molds, a press ram mounted above the support adjacent said means and movable downwardly so as to enter the mold therebeneath to press the material therein into the proper shape, a shuttle plate reciprocable on one end of the support adapted to receive the elements and dispose the same upon said support, said plate being arranged to engage the angular

element at the end of the row of elements on the support, whereby when the plate is moved on the support, a sliding movement is imparted to all of the elements, the movement of the plate being such that upon the inward travel thereof, one of the molds formed by the elements is moved from beneath the press ram and the next successive mold is moved into position therebeneath, the shuttle plate being adapted to receive additional angular elements thereon, and means for holding the elements on the shuttle plate stationary during outward movement of the plate, whereby upon such outward movement the plate slides from beneath the element at the inner end of the plate and said element drops onto the support at the end of the row of elements on such support, thereby being added to said row and forming another mold.

2. A brick manufacturing apparatus including, a stationary support, upstanding sides on said support forming a trough, a plurality of angular unconnected elements movable through the trough and arranged in abutting relation with each other, said elements co-acting with each other and with the sides to provide substantially rectangular molds, means for introducing a cementitious material into the molds, a press ram mounted above the support and movable downwardly so as to enter the mold therebeneath to press the material therein into the proper shape, a shuttle plate reciprocable on one end of the support adapted to receive the elements and dispose the same upon said support, said plate being arranged to engage the angular element at the end of the row of elements on the support, whereby when the plate is moved on the support, a sliding movement is imparted to all of the elements, the movement of the plate being such that upon the inward travel thereof, one of the molds formed by the elements is moved from beneath the press ram and the next successive mold is moved into position therebeneath, the shuttle plate being adapted to receive additional angular elements thereon, means for holding the elements on the shuttle plate stationary during outward movement of the plate, whereby upon such outward movement the plate slides from beneath the element at the inner end of the plate and said element drops onto the support at the end of the row of elements on such support, thereby being added to said row and forming another mold.

3. A brick manufacturing apparatus including, a stationary support, upstanding sides on said support forming a trough, a plurality of angular unconnected elements movable through the trough and arranged in abutting relation with each other, said elements co-acting with each other and with the sides to provide substantially rectangular molds, means for introducing a cementitious material into the molds, each element forming the entire bottom and one longitudinal wall of one of said molds, a press ram mounted above the support and movable downwardly so as to enter the mold therebeneath to press the material therein into the proper shape, a shuttle plate reciprocable on one end of the support adapted to receive the elements and dispose the same upon said support, said plate being arranged to engage the angular element at the end of the row of elements on the support, 75

whereby when the plate is moved on the support, a sliding movement is imparted to all of the elements, the movement of the plate being such that upon the inward travel thereof, one of the molds formed by the elements is moved from beneath the press ram and the next successive mold is moved into position therebeneath, the shuttle plate being adapted to receive additional angular elements thereon, means for holding the elements on the shuttle plate stationary during outward movement of the plate, whereby upon such outward movement the plate slides from beneath the element at the inner end of the plate and said element drops onto the support at the end of the row of elements on such support, thereby being added to said row and forming another mold, latch means for preventing the movement of the row of angular elements on the support while the shuttle plate is moving outwardly to dispose another element on the support, and means for synchronizing the actuation of the press ram with the shuttle plate, whereby said ram moves downwardly into the mold therebeneath when the shuttle plate is moving outwardly and also whereby said ram is raised out of the mold during inward movement of the plate.

4. As a sub-combination in an apparatus, of the character described, a shuttle mechanism including, a flat stationary support, a shuttle plate reciprocable on the support and having its inner end adapted to engage an angular form element on the support to impart movement thereto upon inward movement, said plate being arranged to receive a plurality of angular independent elements thereon and dispose the same upon said support, and a fixed stop on the support and engaging the outermost element on the plate for holding the elements on said plate during outward movement thereof, whereby upon such outward movement of the plate the innermost element may fall therefrom and into position on said support so that upon the next successive inward movement of the plate, the element is slid along the support.

5. A brick manufacturing apparatus including, a stationary support, upstanding sides on said support forming a trough, a plurality of angular unconnected elements movable through the trough and arranged in abutting relation with each other, said elements co-acting with each other and with the sides to provide substantially rectangular molds, means for introducing a cementitious material into the molds, a press ram mounted above the support and movable downwardly so as to enter the mold therebeneath to press the material therein into the proper shape, a shuttle plate reciprocable on one end of the support adapted to receive the elements and dispose the same upon said support, said plate being arranged to engage the angular element at the end of the row of elements on the support, whereby when the plate is moved on the support, a sliding movement is imparted to all of the elements, the movement of the plate being such that upon the inward travel thereof, one of the molds formed by the elements is moved from beneath the press ram and the next successive mold is moved into position therebeneath, the shuttle plate being adapted to receive additional angular elements thereon, and latch means for preventing the movement of the row of angular elements on the support while the shuttle plate is moving outwardly to dispose another element on the support.

NEAL W. HELM.
